UNITED STATES PATENT OFFICE

2,431,123

RECIPROCABLE DOUBLE BUCK LAUNDRY PRESS

Leo M. Kahn, Island Park, N. Y.

Original application May 11, 1939, Serial No. 272,972, now Patent No. 2,383,723, dated August 28, 1945. Divided and this application July 19, 1945, Serial No. 605,898

4 Claims. (Cl. 38—22)

1

This invention relates to presses and more specifically to laundry presses.

In general, it is an object of the invention to provide a device of the character described which will efficiently perform the purposes for which it is intended, which is simple and economical of construction, which can be expeditiously, conveniently and safely manipulated, and which can be readily manufactured and assembled.

Another object of the invention is to provide a press which occupies a minimum of space and which does not have an excessive number of parts, and which also is so constructed that the operator may put the work onto the press at a convenient loading position and preferably at the same or substantially the same loading position for a plurality of bucks; and to provide such a press in which one head and buck may be put through a cycle of any number of operations independently without any other head and buck being operated or while another head and buck stand in pressing engagement; and to provide such a press in which the total pressing force exerted is automatically changed in proportion to the number of bucks and heads which are in pressing engagement.

Other objects of the invention will in part be obvious and will in part appear hereinafter.

The invention accordingly comprises the features of construction, combination of elements and arrangement of parts which will be exemplified in the construction hereinafter set forth and the scope of the application of which will be indicated in the claims.

This application is a division of my copending application Serial No. 272,972, filed May 11, 1939, which issued into Patent No. 2,383,723, dated August 28, 1945.

For a fuller understanding of the nature and objects of the invention, reference should be had to the following detailed description, taken in connection with the accompanying drawing, in which:

Figure 1 is an end view of a machine embodying one form of the invention;

Figure 2 is a front view of the machine shown in Figure 1; and,

Figures 3 and 4 are diagrammatic representations indicating the operation of the device shown in Figures 1 and 2.

The present invention contemplates a space-saving machine and a time-saving machine and one wherein each buck has its loading position positioned conveniently with respect to the hands of the operator. For each buck there is a head with which that buck works. One buck and head

2

may be pressing while another buck and head go through one or more entire cycles of loading and pressing. In this way, all parts of the machine are constantly in use and thereby pressing of various kinds can be carried on without parts of the machine standing idle. The machine may also be run so that the different bucks are alternately loaded and pressed or they may be both in loading or both in pressing position. In Figures 1-4, the heads are somewhat spaced from each other, although substantially vertically aligned, and therefore one of the bucks must move down from the work-receiving position to its head. There are practical disadvantages, e. g., loss of speed, etc., to lower that buck first and then carry it back to its head. In the machine shown in these figures, the buck is carried along a slanting path downward and backward, and before reaching the end of that path it would collide with its head, which is to overlie that buck when the latter reaches its pressing position. Means are provided for avoiding this. Such means operate to remove that head from the path of its descending buck in timed relation automatically. Similarly, the head is removed from the path of its buck just before the latter starts on its slanting upward path to the work-receiving position.

In Figures 1 and 2 of the drawing, 10 denotes a pair of spaced, vertical frames extending between and supported by which is a pair of bucks 11 and 12 and a pair of respective pressing heads 14 and 16. The material to be pressed is laid on one of the bucks while it is forwardly positioned in work-receiving position. It is then moved back into contact with its head and the material pressed between it and the head.

A shaft 18 extends between and is directly supported by the frame 10. At each end of the shaft there is a bell crank 20 having a lower arm 22 and an upper arm 24. Buck 11 has horizontal trunnions 26 at the ends thereof and these are pivotally carried by a link 28 which is also pivotally connected to arm 24. A guide block 30 is carried by each trunnion and has a sliding motion restricted to a linear path by the guides 32. The latter extend from the neighborhood of the head 14 forwardly and downwardly toward a point which may be designated the "work-receiving" position.

Similarly, trunnions 34 at the ends of the lower buck 12 are pivoted at the ends of respective links 36, the other ends of which are pivotally attached to the lower arms 22. Guide blocks 38 on the trunnions 34 are slidable along a linear path which leads downward and backward from

the work-receiving position and which is defined by the guides 40 attached to the frame 10. The guides 32 and 40 are at an angle with each other so as to give intersecting paths for the guide blocks and bucks. The paths may intersect beyond the points where the blocks stop, at the point where the blocks stop, or the blocks may move across and beyond the point of intersection.

Means are provided to rotate the bell crank 20. These may take the form of a crank 42 pivotally attached to the arm 22 and to piston 44 which is slidable in cylinder 46 into which motivating fluid may be introduced, as described below.

There are means for moving head 16 out of the way of buck 12 as the latter is moved downward from the work-receiving position. As shown, the head 16 may be attached to arm 48 of bell crank 50 which is pivoted on frame 10. A spring 52 attached to the frame 10 and arm 54 of the bell crank 50 tends to hold bell crank 50 so that head 16 is out of the path of buck 12. There are other means for fitting head 16 over buck 12 and for pressing it against that buck after the latter has been brought down from work-receiving position. These may comprise a crank 56 pivotally attached at one end to an arm 58 of the bell crank 50 and attached at its other end to a piston 60 in cylinder 62. The arm 58 is so positioned with respect to arm 54 and spring 52 that when fluid pressure is introduced into cylinder 62, the crank 56 forces bell crank 50 to rotate, bringing the head 16 down into pressing engagement with buck 12 when the latter is in its lower backward position.

Figures 3 and 4 show diagrammatically the fluid-operated means and controls therefor for motivating the various parts described above. A main fluid pressure line 64 is connected to a control valve 66 which has a central element 68 rotatable in a valve casing 70. A passageway 72 in element 68 may be positioned to connect line 64 to conduit 74, which leads to cylinder 46 and also to a similar device 76 which, when fluid pressure is introduced into it, causes piston 78 to push head 14 down upon buck 11 against the action of springs 80 which normally keep head 14 spaced from buck 11. The pressure in cylinder 46 causes crank 42 to move out of the cylinder, forcing arm 22 upward until buck 12 is in work-receiving position. Just as arm 22 and arm 24 reach the highest point of their travel, arm 22 contacts valve means 82 in the fluid pressure line leading to cylinder 76. By this means, head 14 is not pushed down until buck 11 is in position to receive it. Beyond the valve 82, in the branch of line 74 which goes to the cylinder 76, there is an offshoot leading to a cylinder 84 from which a piston rod 86 extends as a tongue. That tongue is normally held retracted by spring 88 but, when the pressure is allowed to pass valve 82, it enters cylinder 84, forcing tongue 86 against a lower side of guide block 30 and prevents the buck 11 from being pushed out of position by the head 14, as the latter presses against buck 11.

While the pressure has been causing the parts to move as described, a channel 90 in valve element 68 is connected to valve vent 92 with pressure conduit 94 which leads to cylinder 62 through a pressure control device 96. With no pressure in cylinder 62, spring 52 causes bell crank 50 to rotate so as to lift head 16 out of the path of buck 12 so that the latter may move upward due to the force on arm 22. As will be seen later, the motion of head 16 out of the path of buck 12

takes place before the latter begins its upward and forward motion.

When it is desired that the upper buck 11 shall be brought to work-receiving position and the lower buck 12 be carried back down to pressing position, valve element 68 is rotated counterclockwise, as shown in Figures 3 and 4, by any suitable means such as handle 98. Valve element 68 first reaches a position such that passageway 72 no longer connects the main pressure line 64 and line 74, but does connect vent 92 and line 74. This causes loss of pressure in cylinders 76, 84 and 46 whereby, respectively, head 14 is raised from buck 11 by springs 80, tongue 86 is withdrawn from the path of guide blocks 30 by spring 88 and the upward pressure on arm 22 is no longer exerted by crank 42. In this fashion, the main bell crank is left free to rotate clockwise, under the action of gravity, from the position shown in Figure 1. The rotation of the bell crank 20 is prevented from being too rapid by having a pressure control device 104 in the portion of line 74 which leads to cylinder 46. In this way, cylinder 46 acts as a dash-pot.

A further motion of valve element 68 brings passageway 90 into a position to connect the main pressure line 64 and line 94 leading to cylinder 62. However, since head 16 cannot press onto buck 12 until the latter is in its completely retracted position, the pressure control device or shut-off valve 96 is provided in line 94. Valve 96 is opened by arm 22 when the latter reaches its lowermost position. Buck 12 is then in retracted position. The pressure passes through valve 96 into cylinder 62, moving crank 56 outward and thereby rotating bell crank 50 so as to bring head 16 down against buck 12 with as much force as is desired.

To bring the machine back into the position shown in Figure 3, the valve 66 is turned back from the position shown in Figure 4 to the position shown in Figure 3. This causes the loss of pressure from cylinder 62, the latter being connected to vent 92. Spring 52 then acts to raise head 16 and pressure is admitted to cylinder 46 whereby the entire process for the turning of the main bell crank 20 is begun again. The pressure control element 104 in line 74 delays the setting up of pressure in cylinder 46 and, hence, the raising of arm 22 by a length of time sufficient to permit spring 52 to raise head 16 out of the path of arm 22.

As many possible embodiments may be made of the above invention, and as many changes might be made in the embodiment above set forth, it is to be understood that all matter hereinbefore set forth or shown in the accompanying drawing is to be interpreted as illustrative and not in a limiting sense.

I claim:

1. In a device of the character described, the combination comprising a buck and a head, a second buck and a second head, means for moving one of said bucks along a path between its head and a work-receiving position, means for automatically moving in a reverse direction the other of said bucks in a path between its head and the same work-receiving position, said paths being at an angle with each other, one of said heads being lower than the other of said heads and being directly in the same path of its respective buck, and means for removing said one head from said path of its respective buck.

2. In a device of the character described, the combination comprising a buck and a head, a

second buck and a second head, means for moving one of said bucks along a path between its head and a work-receiving position, means for automatically moving in a reverse direction the other of said bucks in a path between its head and the same work-receiving position, said paths being at an angle with each other, one of said heads being lower than the other of said heads and being directly in the same path of its respective buck, and means for automatically removing 10 said one head from said path of its respective buck whenever its respective buck is about to move into or out of its pressing position.

3. In a device of the character described, the combination comprising a buck and a head, a 15 second buck and a second head, means for moving one of said bucks along a path between its head and a work-receiving position, means for automatically moving in a reverse direction the other of said bucks in a path between its head and the same work-receiving position, said paths being at an angle with each other, and a bell crank, one of said bucks being on one arm of said bell crank and the other of said bucks being on 20 the other arm of said bell crank.

10

15

20

25

4. In a device of the character described, the combination comprising two heads, a bell crank, a buck associated with an arm of said bell crank, a second buck associated with a second arm of 5 said bell crank, said arms lying in the same vertical plane, and means for moving said bell crank from a position in which one of said bucks is adjacent one of said heads and the other of said bucks is in work-receiving position to a position in which said one of said bucks is in work-receiving position and said other of said bucks is adjacent the other of said heads.
